CIRCUIT INTERRUPTER

Winthrop M. Leeds, Pittsburgh, Pa., assignor to
Westinghouse Electric Corporation, East Pittsburgh, Pa., a corporation of Pennsylvania

Application May 18, 1950, Serial No. 162,658

9 Claims. (Cl. 200—150)

1

This invention relates to circuit interrupters, in general, and more particularly to arc-extinguishing structures therefor.

A general object of my invention is to provide an improved circuit interrupter in which the circuit therethrough is more quickly and effectively interrupted. Certain features of my invention have particular application to circuit interrupters of the liquid-break type.

A more specific object is to provide an improved liquid-break type of circuit interrupter in which pressure is generated at one of two serially related arcs and is forced through improved conduit means toward the other serially related arc, known as an interrupting arc, to more readily effect the latter's extinction.

Another object is to provide an improved liquid-break circuit interrupter of the type having a pair of terminal bushings extending into an insulating liquid and having an improved pressure-generating extinguishing unit disposed at the submerged end of one terminal bushing and having an improved interrupting arc-extinguishing unit disposed at the submerged end of the other terminal bushing.

Another object is to provide an improved circuit interrupter of the type set forth in the immediately preceding paragraph in which an improved hollow crossbar construction is provided electrically and hydraulically interconnecting the two units.

Another object is to provide an improved liquid-break circuit interrupter of the type establishing pressure-generating and interrupting arcs in which improved arc-extinguishing units are associated with the pressure-generating and interrupting arcs.

Another object is to provide an improved arrangement of the extinguishing units of a multi-phase circuit interrupter within a single tank.

Further objects and advantages will readily become apparent upon reading the following specification taken in conjunction with the drawings in which:

Figure 1 is a side elevational view, partially in section, of an improved circuit interrupter embodying my invention and shown in the closed circuit position;

Figure 2 is an enlarged side elevational view, partially in vertical section, of the interrupter shown in Figure 1;

Figure 3 is a cross-sectional view taken along the line III—III of Figure 2, looking in the direction of the arrows;

Figure 4 is a sectional view taken along the

2

line IV—IV of Figure 2, looking in the direction of the arrows;

Figure 5 is an enlarged side elevational view, partially in vertical section, of a modified type of circuit interrupter embodying my invention and shown in the partially-open circuit position;

Figure 6 is a sectional view taken along the line VI—VI of Figure 5 looking in the direction of the arrows;

Figure 7 is a side elevational view; partially in vertical section, of a modified type of circuit interrupter embodying my invention and shown in the closed circuit position;

Figure 8 is a sectional view taken along the line VIII—VIII of Figure 7, looking in the direction of the arrows;

Figure 9 is a sectional view taken along the line IX—IX of Figure 7, looking in the direction of the arrows;

Figure 10 is a sectional view, somewhat diagrammatic, indicating the disposition of three poles of a circuit interrupter disposed in a single tank construction, each pole being of the type shown in Figure 7;

Figure 11 is a vertical sectional view through still another modified type of circuit interrupter embodying my invention, the contacts being shown in the closed circuit position;

Figure 12 is a sectional view taken along the line XII—XII of Figure 11, looking in the direction of the arrows; and

Figure 13 is a sectional view taken along the line XIII—XIII of Figure 11, looking in the direction of the arrows.

Referring to the drawings, and more particularly to Figure 1 thereof, the reference numeral 1 designates a tank filled to the level 2 with a suitable arc-extinguishing fluid 3 (in this instance circuit breaker oil). Depending from the cover 4 of the tank 1 are two terminal bushings 5, 6 to the lower ends of which are respectively appended pressure-generating arc-extinguishing unit 7 and interrupting arc-extinguishing unit 8.

Electrically and hydraulically interconnecting the two units 7 and 8 is a tubular fluid conduit 9 actuated vertically in a reciprocal manner by an insulating operating rod 10.

Referring to Figure 2, which more clearly discloses the internal construction of the extinguishing units 7, 8, it will be noted that the pressure-generating arc-extinguishing unit 7 comprises a stationary contact structure 11 cooperable with the upper end 12 of the fluid conduit 9, the pres-

sure-generating arc 13 established therebetween being formed within a pressure-generating chamber generally designated by the reference numeral 14 and defined by a plurality of ring-shaped plates 15. The plates 15 are held together by insulating tie bolts 15a.

The interrupting arc-extinguishing unit 8 includes a stationary contact structure 16 which cooperates with the upper end 17 of the conduit 9 to establish an interrupting arc 18 within a 10 vented interrupting chamber generally designated by the reference numeral 19 and defined by a plurality of ring-shaped insulating plates 20, 21 having different internal diameters. Preferably, one or more vent plates 22 are associated with the upper end of the unit 8, each of which has a configuration more clearly shown in Figure 4.

The operation of the interrupter set forth in Figures 1 to 4 inclusive is as follows. During the opening operation, suitable mechanism (not shown) operates to move the operating rod 10 downwardly, causing simultaneously a separation of the contacts 11, 12 and 16, 17 to establish simultaneously a pressure-generating arc 13 within the pressure-generating chamber 14 and an interrupting arc 18 established within the interrupting chamber 19. Since both units 1, 8 are immersed in oil, oil completely fills the units. Hence, the pressure-generating arc 13 reacts upon the oil within the pressure-generating chamber 14 to form gas which forces oil under pressure out of the pressure-generating chamber 14 through the interior 23 of the crossbar or conduit 9 in the direction of the arrows into the interrupting chamber 19. The flow of oil from unit 1 into unit 8 strikes the interrupting arc 18 and passes out of the unit 19 through the vent opening 24 afforded by the one or more vent plates 22. The flow of oil out of the unit is indicated by the arrow 25.

Extinction of the interrupting arc 18 soon occurs, and the continued downward movement of the operating rod 10 and tubular crossbar 9 causes both ends 12, 17 of the crossbar 9 to pass completely out of the units 1, 8 to the open-circuit disconnect position, indicated by the chain lines 26 of Figure 1.

For moderate voltages (15 to 69 kv.), only one interrupter of the multi-orifice type, as set forth in United States Patent 2,406,469, issued August 27, 1946, and United States Patent 2,467,760, issued April 19, 1949, to Leon R. Ludwig, Winthrop M. Leeds and Benjamin P. Baker and assigned to the assignee of the instant application, is required for the interrupting duty. However, the conventional oil breaker uses duplicate interrupting units on the two terminals of each pole. A great simplification can be achieved in the contact structure, if, instead of putting both a pressure-generating and interrupting gap on each terminal, the pressure for oil flow can be generated in a single gap on one terminal and transmitted to a single interrupting gap on the other terminal. The interrupting structure set forth in Figures 1 to 4 describes features for accomplishing this object. It will be noted that I have used a tubular moving contact crossarm 9 combining the functions of current conduction and fluid flow transmission between the pressure-generating unit 1 and the interrupting unit 8. The interrupter set forth in Figures 1 to 4 shows one of the simplest embodiments of my invention where the moving contact and crossarm 9 may be made of a simple, U-shaped, bent metallic tube, for instance, of copper or aluminum,

Pressure generated in the left-hand chamber 14 forces oil through the tube 9 to the top vented interrupting chamber 19 at the right, as viewed in Figure 2, where the arc is deionized and extinguished.

The arrangement set forth in Figures 5 and 6 differs from Figures 1 to 4 in the right-hand interrupting chamber only, with a piston construction associated with the left-hand chamber for the prevention of cavitation, and also to speed up the interruption of low currents where the self-generated action is weak. This interrupter will now be described.

It will be noted that I have provided a piston arrangement, generally designated by the reference numeral 28, associated with the left-hand pressure-generating chamber 1, a pressure-generating arc 13 being established, as before, between the stationary contact structure 11 and the upper end 12 of the crossbar 9. As before, an insulating operating rod 10 causes the vertical actuation of the tubular fluid conduit 9.

The right-hand interrupting chamber 29 is of modified construction, as compared with the interrupting chamber 19 of the unit 8 of Figure 2, and in this instance forms a multi-orifice interrupting structure generally designated by the reference numeral 30 and follows the teachings set forth in the aforesaid patents.

Observing the interrupting unit 29, taken in conjunction with the cross-sectional view 6, it will be noted that an upstanding, rod-shaped contact portion 31 is integrally formed with the conduit 9 with vents 32 leading out of the tubular conduit 9 just below the rod contact 31 as shown in Figure 5. The rod contact 31 cooperates with the stationary contact structure 16 of the unit 29 to establish an interrupting arc 18 within the multi-orifice interrupting structure 30.

The multi-orifice interrupting structure 30 is made up of a plurality of contiguously disposed insulating plates, these plates being of three different types. The first type of plate is called a vent plate and is generally designated by the reference numeral 33 of Figure 6. The vent plate 33 is of composite construction and in this instance includes two laterally spaced half plates 34 spaced apart to form two opposed vent passages 35. Immediately above and below each vent plate 33 is an orifice plate 36, the configuration of which is more clearly shown in Figure 6. The orifice plate 36 has an aperture 37 through which the rod-shaped, movable interrupting contact 31 passes. The orifice plate 36 also has a pair of kidney-shaped openings 38, as was the case with the vent plate 33, the purpose for which will be more fully explained hereinafter.

Adjacent to each orifice plate 36 is an insulating inlet plate 40 having a configuration more clearly shown by the dotted lines of Figure 6. The cutout portion 40a permits entrance of oil from the two vertical passages 41, formed by the alignment of the several openings 38, to pass inwardly toward the interrupting arc 18. The oil then passes upwardly and downwardly through the orifices 37 provided by the orifice plates 36 to pass out of the interrupting unit 29 through the two opposed vent passages 35. As mentioned previously, the passage configuration conforms to the teachings of the aforesaid patents.

It will be noted that with the construction set forth in Figures 5 and 6, the deionizing action is particularly effective by the multi-orifice interrupting structure 30 provided. Also, the piston 28 biased downwardly by a compression spring

42 prevents cavitation, or low pressure conditions, taking place within the unit 7 due to the fact that the tubular fluid conduit 9 moves out of the chambers 7, 29. The piston 28 is biased by the spring 42 so as to follow behind the moving contact 12 when the pressure falls too low. This piston area may either just compensate for the contact displacement of the contact 12, or be larger to provide positive pumping action to speed up the interruption of low currents where the self-generated action is weak. The piston construction is disclosed and claimed in United States Patent application Serial No. 162,684, filed May 18, 1950, by Robert C. Dickinson, and assigned to the assignee of the instant application.

It will be observed that the oil flows out of the pressure-generating chamber 14 through the interior 23 of the tubular fluid conduit 9 in the direction indicated by the arrows. The oil passes out of the tubular conduit 9 through the vent openings 32 into a pressure chamber 32a where it passes upwardly through the two vertical passages 41 and toward the interrupting arc 18 in the manner previously described. Following an interrupting operation, the contacts 12, 31 pass completely out of the respective units 7, 29 to an external disconnect gap position (not shown).

The interrupting structure set forth in Figures 7 to 10 discloses a modification in which the contact rod and oil flow tube are separated before entering the chambers for improved multi-flow action and shorter grid length. Referring to these figures, it will be noted that I have provided an improved pressure-generating arc-extinguishing unit 43, which includes a stationary contact structure 11 and a piston arrangement 28, as shown in Figure 5, to prevent cavitation and speed up low current interruption. In this embodiment of my invention, a modified tubular fluid conduit 44 is utilized having a pressure-generating rod contact 45 and an upstanding tubular portion 46 which extends into the interior of the unit 43. A pressure-generating arc (not shown) is established between the contacts 11, 45 within a multi-orifice pressure-generating chamber, generally designated by the reference numeral 47. The construction of the multi-orifice pressure-generating chamber 47 is more clearly disclosed in Figure 8.

Referring to Figure 8, it will be observed that there are three different types of insulating plates utilized, disposed in contiguous relation. A pocket insulating plate 48 has a configuration disclosed by the full lines in Figure 8 with two apertures 49, 50 formed therein. The aperture 49 traps oil along the path of movement of the pressure-generating arc (not shown). The aperture 50 provides upon alignment with apertures 50 of the other plates a vertical passage 51, through which the tubular portion 46 of the cross-bar 44 moves. The second plate in the pressure-generating chamber 47 is called an orifice plate and is designated by the reference character 52. This plate, as shown in Figure 8, has an aperture 53 formed therein, but also has a smaller aperture 53 than the aperture 49 associated with the plate 48.

Two such plates 52 are disposed on opposite sides of each pocket plate 48. The third type of plate utilized in the pressure-generating chamber 47 is herein called an inlet plate 54, and is provided with a cutout portion 55, as indicated by the dotted lines of Figure 8. The inlet plate 54 permits the passage of oil under pressure from the pressure-generating arc through the cutout

portions 55 and into the vertical flow passage 51, where the oil enters the upper end of the tubular member 46 to pass therethrough in the direction indicated by the arrows to the multi-orifice interrupting chamber 56.

The multi-orifice interrupting chamber 56 includes three different types of plates. The first type is the same as the orifice plate 52 previously described in connection with the pressure-generating chamber 47. The second type of plate is called a vent plate and is herein designated by the reference character 57. The vent plate 57 is a composite plate, and is formed by the cooperation of two half plates 58, 59, as shown more clearly in Fig. 9. The half plate 58 has an aperture 50 passing therethrough. The lateral spacing between the half plates 58, 59 provides two opposed vent passages 60 passing out of the multi-orifice interrupting, arc-extinguish unit 56. The third type of plate is identical to the inlet plate 54 previously described in connection with the pressure-generating chamber 47 and hence need not be further described.

The oil flow passing through the upstanding portion 61 of the tubular fluid conduit 44 successively passes through the inlet passages 62 toward the interrupting arc, the latter being established between the stationary contact structure 16 and the rod-shaped interrupting contact 67. The oil, after contacting the interrupting arc, passes through the apertures 53 to vent out of the interrupting, arc-extinguish unit 56 through the opposed vent passages 60. Arc extinction soon occurs, and the piston structures 28, biased downwardly by the compression springs 42, afford a flushing oil flow following high current interruption, or a positive oil flow during low current interruption.

It will be noted that the advantage of this construction is the short overall vertical length of the extinguishing units 64, 65 as compared with the vertical length of the units 7, 29 of Figure 5. Also, it will be noted that an improved multi-flow oil flow action is present within the pressure-generating chamber 47, as contrasted with the pressure-generating chamber 14 of Figures 2 and 5, in which a plain break occurred within a relatively open space.

Where it is desired to interrupt a three-phase circuit, the three poles of the breaker, each of which is of the type shown in Figure 7, may be disposed within a tank 66 of Figure 10. The middle pole may have the units 64, 65 thereof each turned 180°, as shown, to keep the length of the tube 44 short, when the middle units are separated farther than the outer poles to improve electrical clearances. Also the vented units 65 are preferably located two on one side of the breaker centerline and one on the other to separate the expelled gases as far as possible. This prevents flashover or shorting between the phases or between any extinguishing unit and the grounded tank 66.

Figures 11 to 13 disclose still a further embodiment of my invention. In the arrangement disclosed in these figures, it will be observed that the hollow fluid conduit 69 has a large internal diameter, the reason for which will be more apparent hereinafter. Two upstanding tubes 70 have their interiors 71 hydraulically interconnected with the interior 72 of the hollow conduit 69. Piston structures 28 are employed, having the same functions as heretofore discussed. The pressure-generating contact 45 separates from the stationary finger contacts 11 to establish a pres-

sure-generating arc (not shown) within a multi-orifice pressure-generating interrupting structure, generally designated by the reference numeral 73. The pressure-generating interrupting structure 73 is composed of a plurality of suitably configured insulating plates disposed in contiguous relation, and having a shape more fully disclosed in Figure 12. There are three different types of plates. The first type of plate is herein called an inlet plate being designated by the reference numeral 74. The inlet plate 74 has a cutout portion 75 removed therefrom so that oil may pass from the pressure-generating arc passage 76 to the vertical flow passages 51. From the vertical flow passages 51, the oil enters the tubes 70 to pass through the conduit 69 to the interrupting arc-extinguishing unit 77.

The second type of plate is herein called a pocket plate 78 and has a configuration more clearly shown by the full lines of Figure 12. The pocket plate 78 has a relatively large central aperture 79 and two oppositely disposed apertures 50, which, upon alignment with other apertures 50, form the vertical flow passages 51 through which the tubes 70 pass.

The third type of plate is herein called an orifice plate 80 and has the same configuration as the pocket plate 78, except the central aperture 81 is of smaller diameter than the aperture 79 of the pocket plate 78.

Upon the establishment of the pressure-generating arc (not shown) between the contacts 11, 45a, the oil within the multi-orifice, pressure-generating, arc-extinguishing unit 82 is vaporized and passes in opposite directions out through the inlet passages 83 provided by the cutout portion 75 to pass into the two vertical flow passages 51. The oil passes downwardly through the tubes 70 and into the hollow conduit 69 of large internal diameter.

The right-hand, multi-flow, interrupting, arc-extinguishing unit 77 is composed of three different types of plates, two of which have a construction identical to the plates heretofore discussed in connection with the unit 82 namely, plates 74 and 80. However, in place of the pocket plates 78, heretofore discussed in connection with the pressure-generating unit 82, vent plates 84 of composite construction are employed shown by the full lines in Figure 13. The composite vent plates 84 are formed by the lateral spacing of two half plates 85, 86 to form two opposed vent passages 87 leading out of the unit 77.

The operation of the interrupter of Figures 11 to 13 will now be described. Upon downward opening movement of the operating rod 10, conduit 69 likewise moves downwardly carrying with it the movable contacts 45a, 88 which respectively separate from the stationary contacts 11, 16 to draw, respectively, a pressure-generating arc and an interrupting arc (not shown).

The pressure-generating arc generates pressure within the multi-orifice, pressure-generating chamber 73 to force oil out through the inlet passages 83 into the vertical flow passages 51, and down through the pair of tubes 70 to pass laterally through the hollow conduit 69. The oil, under pressure, then passes upwardly through the tubes 89, 90 disposed, respectively, within the vertical flow passages 91, 92 to pass inwardly through the inlet passages 83 provided by the inlet plates 74. After passing through the apertures 81 provided by the orifice plates 80, and hence into intimate contact with the interrupting arc, the oil then passes laterally outwardly out of the inter-

rupting unit 77 through the opposed vent passages 81 provided by the vent plates 84. The resulting effective deionizing conditions brought about by the oil flow quickly effects extinction of the interrupting arc, and the circuit is open.

Continued downward opening movement of the operating rod 10 and tubular conduit 69 brings about a withdrawal of the contacts 45a, 88 and tubes 70, 89 and 91 out of the units 82, 77 to the open-circuit, disconnect position (not shown).

From the foregoing description of a few embodiments of my invention, it will be apparent that I have provided an improved circuit interrupter in which fluid flow is effectively brought about. Also, it will be apparent that I have provided an improved conduit construction not only electrically connecting the units disposed at the lower ends of the terminal bushings 5, 6, but also provided a hydraulic transmission between the two units to bring about effective oil flow. The structure is simple, compact and readily accessible. The multi-orifice, pressure-generating chamber construction set forth in Figures 7 and 11 is very effective because of the oil trapped in pockets and held closely to the arc. Also, during interruption of low currents, effective deionizing conditions are brought to bear upon the pressure-generating arc as well as upon the interrupting arc. The piston construction provided not only affords a flushing flow of fluid following high current interruption, but also provides a desired piston flow during low current interruption, when the pressure generated at the pressure-generating arc may be relatively weak.

Although I have shown and described specific structures, it is to be clearly understood that the same were merely for the purpose of illustration, and that changes and modifications may readily be made therein by those skilled in the art without departing from the spirit and scope of the appended claims.

I claim as my invention:

1. A circuit interrupter including a vented interrupting chamber having a pair of substantially parallel passages disposed therein, a relatively stationary contact disposed at one end of one of the passages, a movable conducting conduit having a movable rod-shaped contact secured thereto and movable therewith, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, means for forcing fluid through the conduit and through the tubular portion thereof, and the fluid passing successively through the spaced inlet passages toward the interrupting arc as a result of the opening movement of the tubular portion along said other passage.

2. A circuit interrupter including a vented interrupting chamber having a pair of substantially parallel passages disposed therein, a relatively stationary contact disposed at one end of one of the passages, a movable conducting conduit having a movable rod-shaped contact secured thereto and movable therewith, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, means for forcing fluid through the conduit and through the tubular portion thereof, and

the fluid passing successively through the spaced inlet passages toward the interrupting arc as a result of the opening movement of the tubular portion along said other passage, and means for laterally venting the interrupting chamber at a plurality of spaced points along said one passage.

3. A circuit interrupter including a substantially confined pressure-generating chamber, a vented interrupting chamber spaced away from the pressure-generating chamber and having a pair of substantially parallel passages disposed therein, a relatively stationary contact disposed at one end of one of the passages within the interrupting chamber, a movable conducting conduit interconnecting the pressure-generating chamber with the interrupting chamber and having a movable rod-shaped contact secured thereto, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, the pressure established within the pressure-generating chamber forcing fluid through the conduit and through the tubular portion thereof, and the fluid passing successively through the spaced inlet passages toward the interrupting arc as a result of the opening movement of the tubular portion along said other passage.

4. A circuit interrupter including a substantially confined pressure-generating chamber, a vented interrupting chamber spaced away from the pressure-generating chamber and having a pair of substantially parallel passages disposed therein, a relatively stationary contact disposed at one end of one of the passages within the interrupting chamber, a movable conducting conduit interconnecting the pressure-generating chamber with the interrupting chamber and having a movable rod-shaped contact secured thereto, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, the pressure established within the pressure-generating chamber forcing fluid through the conduit and through the tubular portion thereof, the fluid passing successively through the spaced inlet passages toward the interrupting arc as a result of the opening movement of the tubular portion along said other passage, and means for laterally venting the interrupting chamber at a plurality of spaced points along said one passage.

5. A circuit interrupter including a vented interrupting chamber having a pair of substantially parallel passages disposed therein, a relatively stationary contact disposed at one end of one of the passages, a movable conducting conduit having a movable rod-shaped contact secured thereto and movable therewith, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, means for forcing fluid through the conduit and through the tubular portion thereof, and

the fluid passing through the spaced inlet passages toward the interrupting arc.

6. A circuit interrupter including a vented interrupting chamber having a pair of substantially parallel passages disposed therein, a relatively stationary contact disposed at one end of one of the passages, a movable conducting conduit having a movable rod-shaped contact secured thereto and movable therewith, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, means for forcing fluid through the conduit and through the tubular portion thereof, the fluid passing through the spaced inlet passages toward the interrupting arc, and means for laterally venting the interrupting chamber at a plurality of spaced points along said one passage.

7. A circuit interrupter including a substantially confined pressure-generating chamber, a vented interrupting chamber spaced away from the pressure-generating chamber and having a pair of substantially parallel passages disposed therein, a relatively stationary contact disposed at one end of one of the passages within the interrupting chamber, a movable conducting conduit interconnecting the pressure-generating chamber with the interrupting chamber and having a movable rod-shaped contact secured thereto, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, the pressure established within the pressure-generating chamber forcing fluid through the conduit and through the tubular portion thereof, and the fluid passing through the spaced inlet passages toward the interrupting arc.

8. A circuit interrupter including a substantially confined pressure-generating chamber, a vented interrupting chamber spaced away from the pressure-generating chamber and having a pair of substantially parallel passages disposed therein, a relatively stationary contact disposed at one end of one of the passages within the interrupting chamber, a movable conducting conduit interconnecting the pressure-generating chamber with the interrupting chamber and having a movable rod-shaped contact secured thereto, the movable rod-shaped contact cooperating with the stationary contact within said one passage to establish an interrupting arc therealong, the conduit having a tubular portion entering and movable along the other of said passages, a plurality of spaced inlet passages interconnecting the two aforesaid passages, the pressure established within the pressure-generating chamber forcing fluid through the conduit and through the tubular portion thereof, the fluid passing through the spaced inlet passages toward the interrupting arc, and means for laterally venting the interrupting chamber at a plurality of spaced points along said one passage.

9. A circuit interrupter including a substantially enclosed arc-extinguishing unit having a pair of substantially parallel passages disposed

11

therein, a relatively stationary contact disposed in one of the passages, a movable conducting conduit having a movable rod-shaped contact secured thereto and movable therewith, the movable rod-shaped contact cooperating with the stationary contact within said one passage to establish an arc therealong, the conduit having a tubular portion movable along the other of said passages, a plurality of spaced inlet passages interconnecting the two aforesaid passages, and the fluid passing through the inlet passages and also through the conduit during the opening operation.
